ELECTROLYTIC DEVICE

Joseph L. Collins and Alexander Durant, Jr.,
North Adams, Mass., assignors to Sprague
Specialties Company, North Adams, Mass., a
corporation of Massachusetts

Application July 21, 1937, Serial No. 154,906

2 Claims. (Cl. 220—44)

The present invention relates to electrolytic devices and the like, and more particularly to venting means for the escape of gases formed in the operation of such devices.

5 In various types of electrolytic devices, for instance in electrolytic condensers, in connection with which the invention will be described, a liquid- and air-tight sealing of the device is of great importance, so as to prevent loss of the 10 electrolyte, as well as creepage of the salt of the electrolyte, and also to prevent contamination of the electrolyte.

On the other hand, the gases liberated during 15 the operation of electrolytic condensers require venting means for their escape.

Various venting means have been therefore suggested for such condensers, most of which, however, have the common drawback of permitting the electrolyte to be carried away with 20 the escaping gases. A widely-used venting means which overcomes this difficulty is one in which the gases escape through a semi-permeable gasket, as described in U. S. A. Patent #2,005,055 to Robert Sprague et al.

25 Such a semi-permeable gasket is as a rule crimpedly interposed between the open end of the condenser container and a closure member, and usually consists of a fabric washer impregnated with wax or other water-repellent material.

In the usual types of wet electrolytic condensers and under usual operating conditions, the rate at which gas is liberated in the condenser is less than the rate at which these 35 gases can pass through the above-described venting means. However, even in some types of wet electrolytic condensers, and particularly in dry electrolytic condensers—which have a lower heat capacity and poorer heat dissipation than wet 40 electrolytic condensers—conditions may arise which cause such a large amount of gas liberation and at such a high rate that the usual venting means are unable to handle them.

As a result, pressures of such magnitude may 45 build up in the condenser container as to cause its violent explosion. While such instances are comparatively rare, they may occur, for example, if a condenser is operated for a prolonged time at a voltage much in excess of its rated 50 voltage. Continued operation at excess voltages not only increases gas liberation at the electrodes due to the electrolytic reaction, but may cause intense evaporation of the electrolyte due to excessive heat development. This excessive heat 55 development is due to the cumulative action of

increased leakage current and power factor which occurs upon prolonged application of excessive voltages, i. e., at higher than normal voltage the leakage current increases, causing greater heat development, which in turn increases the power 5 factor of the condenser. The increased power factor further increases heat development, which in turn causes a further increase in the leakage current, and so on, and unless the heat dissipation of the condenser takes care of it, the condenser will be heated up to a point where a violent evaporation of the electrolyte takes place, resulting in the explosion of the condenser container.

The object of the present invention is to provide a combination of venting means, a portion of which takes care of the normal venting, and another portion of which becomes effective only when within the condenser a high gas pressure of a predetermined value has built up, which 20 value is selected to be lower than the pressure which would destroy the container.

According to the invention we provide venting means to take care of the normal gas liberation, and emergency venting means to be effected only 25 when the pressure in the condenser container reaches a comparatively high value.

In accordance with the invention, the emergency venting means comprise a weakened portion of the condenser container, which is pierced 30 by a pressure of predetermined value, such value being so selected as to be by a safe margin lower than the pressure which would cause explosion of the container.

Preferably we provide the weakened portion 35 of the container in a cover member and in such a manner that piercing of this portion provides for the escaping gases a low-resistant passage of a predetermined cross section.

Such a weakened cover portion can be conveniently obtained and substantially without extra cost with the generally used molded covers made of Bakelite, hard rubber and like materials.

In the preferred embodiment of the invention 45 the normal and the emergency venting means are partly interrelated.

In the drawing forming part of the specification:

Figure 1 is a cross-sectional view of a condenser embodying the venting means of the invention;

Fig. 2 is an enlarged cross-sectional view of the cover of the condenser in Fig. 1 taken along the lines 2—2 of Fig. 3;

Fig. 3 is a bottom plan view of the cover of Fig. 2.

Referring to the drawing, the condenser proper, designated as 11, consists of two electrode foils 5 12 and 13 of which at least one is of film-forming metal, for instance of aluminum, tantalum, zirconium, etc., and is provided with a film, usually formed on the electrode electrolytically and prior to the assembly of the condenser.

10 Interposed between the electrode foils are spacers 14—14 which, together with the foils 12 and 13, are wound into a roll. The spacers 14 consist of a suitable absorbent material, such as gauze, paper or the like.

15 The electrolyte 15 carried by the spacers, as a rule comprises as ionogen a weak acid of the type of boric acid, phosphoric acid, citric acid, etc., and preferably also a salt of a weak acid, which, however, does not need to be the salt of 20 the acid used. As ionizing solvent the electrolyte comprises as a rule a polyhydric alcohol, for instance glycerine, ethylene glycol, etc., and also a fixed amount of water. The electrolyte may also comprise one or more inert substances which may 25 serve to increase its viscosity, for instance bentonite, starch, silica gel, etc., and/or a finely divided conducting material, such as magnetite, lead peroxide, graphite, etc. to increase its conductivity as well as its viscosity.

30 The spacers 14 are impregnated with the electrolyte 15 either prior to or after the assembly into a roll. The condenser 11 is surrounded by a cylindrical metallic container 10, from which it is suitably insulated by air spaces or insulating 35 spacers.

35 The annular cover 16, inserted in the open end of container 10 and abutting against an annular indentation 50 thereof, is preferably a molding of a suitable insulating material, as hard rubber, 40 Bakelite, or the like. At its top the cover 16 is provided with a peripheral recess 27, the flat surface of said recessed portion being provided with a narrow annular ridge 35.

45 Close to the periphery of the top face 53 of its not recessed portion, the cover is provided with a small cylindrical cavity 31 extending downwardly to the level of surface 54 and having thin side and top walls 33 and 34 respectively, these forming the weakened portions of the cover.

50 Beneath and concentrically with the cavity 31 there is provided in the cover 16 a cylindrical cavity 30 of larger diameter, the cavity 30 extending to the bottom face 56 of cover 16.

55 As appears from Figs. 2 and 3, in the top face 54 of the recessed portion of the cover a crescent-shaped opening or fissure 32 is formed.

The cover is also provided with two terminal posts 17 and 18, which are preferably molded into the cover and to which are connected the electrodes 12 and 13 by connecting strips 19 and 20 respectively.

Outside electrical connection of the electrodes can be made by means of nuts 21 and 22 secured to the threaded ends of the posts 17 and 18.

60 Preferably the cover 16 is provided with projecting flat-faced bosses 51—51 cooperating with the nuts 21 and 22.

65 A semi-permeable washer-shaped gasket 28 of impregnated fabric or a washer of soft rubber, to 70 which water-repellent material has been added, is disposed in recess 27 and is pressed against the cover 16 by the crimped end 60 of the container 10. The ridge 35 insures the proper location of the gasket 28 and its tight engagement with the cover 16.

As will be noted from Figs. 2 and 3, in the portion 61, which covers the crescent fissure 32, the gasket 28 is directly exposed to the pressure existing within the container; this portion of the gasket serving as the venting means through 5 which the gases escape during the normal operation of the condenser. In case the gasket is of semi-permeable material the gases pass through it without necessarily lifting the exposed gasket portion 61. However, if the gaskets are non-porous, for example made of soft rubber, the exposed gasket portion 61 is lifted by the pressure of the gases and permits their escape through the opening so created. However, if because of unusual conditions, for example the prolonged application of a voltage much in excess of the rated voltage of the condenser, the gas liberation assumes such proportions as to tend to build up in the container 10 a pressure which would blow up the container, before such critical pressure is built up, i. e. at a pre-selected lower value, the cover will be pierced at its weakened portion. Such piercing of the cover, i. e. the forcible ejection of the wall portions 33 and 34, offers a passage of the cross section of cavity 31 for the escape of the gases, which is sufficiently large to permit the venting of the gases even under such unusual conditions.

It should be noted that the large amount of heat generated in the condenser incidental to the prolonged application of an excessive voltage, further weakens the wall portions 33 and 34 and thus facilitates their ejection.

The relative and actual dimensions of the venting means depend on a number of factors, such as the amount of gases required to be handled by the normal venting means, the pressure at which the piercing of the cover is to take place, overall dimensions and material of the cover, etc.

For example, in the case of a hard rubber cover having a diameter of about $1\frac{3}{8}$ " and being $\frac{1}{4}$ " thick, to obtain a puncturing of the cover when the pressure built up in the container has reached a value of about 100 lbs. per square inch, the following dimensions were found suitable:

Cavity 30: diameter $\frac{1}{4}$ ", height $\frac{3}{16}$ ".

Cavity 31: diameter $\frac{1}{8}$ ", height $\frac{1}{32}$ ".

Thickness of wall 34: $\frac{1}{32}$ ".

Thickness of thinnest portion of wall 33: $\frac{1}{32}$ ". Distance of common axis of cavities 30 and 31 from edge of cover: $\frac{7}{32}$ ".

Maximum width of crescent fissure 32: $\frac{1}{32}$ ".

The above dimensions are given as an illustration only, as wide variations may take place in same in view of the various factors involved.

While we have described our invention in connection with specific embodiments and in specific examples, we do not wish to be limited thereto, but desire the appended claims to be construed as broadly as permissible in view of the prior art.

What we claim is:

1. Venting means for electrolytic condensers having a container closed by a cover, said means comprising a vent gasket and a recessed portion in the cover to receive same, said cover being provided with two concentric cavities, one on top of the other, the upper cavity being of very small diameter and the lower cavity of somewhat larger diameter, the upper cavity being partly surrounded by a thin wall portion and the lower cavity having a fissure under said gasket, said venting means being adapted to vent the gases developed in the normal operation of the condenser through the bottom cavity and the gasket 75

portion overlying the fissure, and to vent gases at pressures considerably in excess of the normal pressures by the rupture of said thin wall portions to thereby liberate the gas through said bottom cavity and through the opening provided by the removal of said wall portions.

2. In an electrolytic device, a container and a cover for said container, means to permit the escape of gases developed in said device, said 10 means comprising a low-pressure vent and a high-

pressure vent in cooperative relationship with each other, said high-pressure vent comprising a weakened portion of said cover adapted to be detached from the rest of said cover, said low-pressure vent comprising a fissure at said weakened portion of the cover and an overlying semi-permeable gasket secured over said fissure by said container. 5
